CRADLE STRUCTURE FOR COIN HANDLING EQUIPMENT

Merrel P. Haverstick, St. Louis, Mo., assignor of one-half to The Vendo Company, Kansas City, Mo., a corporation of Missouri, and of one-half to Coin Acceptors, Inc., St. Louis, Mo., a corporation of Missouri

Filed Apr. 30, 1962, Ser. No. 190,955
9 Claims. (Cl. 194—182)

This invention relates to coin handling equipment and especially to apparatus used in coin actuated machines for separating coins into the various denominations thereof to permit totalization of the value of the same, and also capable of segregating genuine coins from spurious discs. The coin selecting apparatus has novel structure thereon for separating coins of one denomination and size from coins of a second denomination and smaller size in an efficient manner employing components having maximum tolerance characteristics, and at a practical cost.

Although the coin selecting structure of the present invention has utility for use in segregating many types of coins, the components have primary utility in a coin selecting device capable of handling quarters, nickels, dimes and pennies, for separating dimes from pennies and directing respective coins into coin accepting pathways therefor forming a part of the complete unit.

Coin selectors of the "4-in-1" type have been employed for a number of years and having structure thereon for segregating the coins into the different denominations thereof and directing the individual coins to corresponding coin accepting tracks or pathways for the same through the accepting equipment.

In prior coin separating apparatus capable of handling four different sizes of coins, it has been conventional to effect separation of dimes from pennies by providing an aperture in the main vertical wall of the separating structure and of a size sufficient to pass dimes but not pennies. In this manner, by directing both the dimes and pennies downwardly along one face of the upright wall, a swingable member may be provided in the aperture to effect movement of both dimes and pennies toward the aperture as the coins gravitate downwardly through the apparatus. However, only the dimes will pass through the aperture and therefore, such dimes are then directed to a coin accepting track for the same, whereas the pennies continue downwardly and are tested by further components designed to segregate valid pennies from spurious discs or the like. It can be recognized that the aperture in the main wall of the selecting apparatus must have extremely critical dimensions in order to pass only genuine dimes and to exclude pennies therefrom, and also problems are encountered in preventing the lower margin of each of the dimes engaging the lower portion of the wall around the dime aperture, and which would effect hanging up of dimes in the aperture in a manner to block the separating apparatus and requiring removal of the same from a vending machine or the like, or manual scavenging of the coins in the usual manner.

It is therefore the primary object of the present invention to provide coin selecting apparatus provided with novel means therein for segregating coins of one size from coins of another size wherein it is required that one size coins be directed to a coin track on the rear face of the main upright wall of the apparatus while the other size coins are diverted into a coin track therefor on the front face of the main wall, and with the requirement of an aperture of critical size for segregating the coins being completely obviated so as to increase the tolerances of the various parts, simplify the construction and assembly of the over-all unit, and provide a device which is

2

much more efficient and accurate than prior structures of this type.

An additional important object of the invention is to provide coin selecting apparatus as described which is not only readily adapted for handling United States coins, but also may be employed to segregate various types of foreign coinage, without substantial modification of the over-all apparatus being required.

A further important aim of the invention is to provide coin handling equipment for separating coins of different size and value from one another wherein is included rotatable cradle structure having legs thereon disposed to receive a coin of one size and value to divert the coin into a pathway therefor upon rotation of the cradle, while coins of smaller size may pass through the legs of the cradle and thereby permitting association of a coin diverting element with the cradle to effect direction of the coins passing between the legs of the cradle to a coin track for such smaller coins in spaced relationship to the coin track of the coins diverted by the cradle. Also an important object of the invention is to provide coin handling apparatus as set forth above wherein the coins passing through the legs of the cradle may be diverted by the element associated with the cradle, through an aperture of non-critical size in the main wall of the coin handling equipment and in a manner such that there is no possibility of the lower margin of the coin being obstructed by the wall thickness of the aperture.

Other objects and important details of the present apparatus will become obvious or be explained in greater detail as the specification progresses.

In the drawings:

FIGURE 1 is a front elevational view of coin selecting apparatus embodying the novel structure of the present invention for separating dimes and pennies introduced into the apparatus;

FIG. 2 is a fragmentary, elevational view of the rear face of one of the swingable gate units forming a part of the over-all apparatus illustrated in FIG. 1;

FIG. 3 is a fragmentary, elevational view similar to FIG. 2 and illustrating the manner in which cradle structure for separating pennies from dimes, is rotated during diversion of a penny into the coin track therefor;

FIG. 4 is an elevational view of the structure shown in FIG. 3, and indicating the position of the penny cradle immediately prior to gravitation of the penny from such cradle;

FIG. 5 is an elevational view similar to FIGS. 3 and 4 and indicating the disposition of a dime passing between the legs of the penny cradle and being diverted toward an aperture in the main wall of the coin handling equipment for direction to a coin track for the dime;

FIG. 6 is a view of the dime separator as shown in FIG. 5 and indicating the relative disposition of the dime as the same moves downwardly through an additional increment of travel during diversion of the dime toward the coin track therefor;

FIG. 7 is an exploded perspective view of the rear faces of the penny cradle and dime diverting element forming the subject matter of the present invention;

FIG. 8 is an exploded perspective view of the opposite faces of the cradle and dime diverting element illustrated in FIG. 7;

FIG. 9 is a vertical sectional view taken substantially on the line 9—9 of FIG. 1 and illustrating schematically the position of a penny as the same gravitates from the cradle structure therefor, but with the cradle being located in its normal unoperated position; and

FIG. 10 is also a vertical sectional view taken on the line 9—9 of FIG. 1 and illustrating schematically the path of travel of a dime as the same passes through the separating structure.

The coin selecting apparatus designated generally by the numeral 10 in the drawings is designed to handle United States quarters, nickels, dimes and pennies and thereby capable of segregating the coins into the different denominations thereof, and also accepting only genuine coins while spurious discs and coins of improper size and weight are rejected. Since only the portion of apparatus 10 relating to segregation of dimes from pennies forms the subject matter of the present invention, the remaining components of apparatus 10 will be described only in general terms since the construction and operation thereof will be obvious to those skilled in this art. The frame 11 includes a normally upright, rectangular wall 12 having a pair of integral, outwardly projecting, parallel, vertical side walls 14 and 16 integral with opposed side margins of main wall 12. The main gate unit 18 of apparatus 10 is rotatably mounted on side wall 16 for swinging movement about the axis of pin means 20 and it is to be understood that gate unit 18 has a number of projecting portions thereon extending toward main wall 12 and cooperating with the latter to define a number of separate coin tracks as for example, the pathways for coins of quarter and nickel denominations. A secondary gate unit 22 is also rotatably mounted on pin means 20 beneath gate unit 18 and cooperates with the latter to define the coin pathways or tracks referred to above. A scavenger section 24 rotatable about the axis of pin means 20 and located in overlying relationship to the gate units 18 and 22, has a series of inwardly projecting legs thereon adapted to scavenge coins from the cradles to be described herein-after, as will be apparent as the description progresses.

Plate member 26 having an outwardly flared upper portion is cooperable with the generally U-shaped element 28 mounted on the upper extremity of main wall 12, to define a coin entrance whereby quarters, nickels, dimes and pennies may be introduced into apparatus 10 from a suitable source such as the coin chute of a vending machine or the like mounting the coin handling equipment. Quarters introduced into the coin entrance of apparatus 10 are directed downwardly toward the quarter cradle 28 where the coin comes to rest on the spaced legs of such cradle to effect rotation thereof in a clockwise direction viewing FIG. 1, and against the counterweight on the cradle to cause the coin to be diverted into the quarter pathway or track for movement therealong to cause the coin to be subjected to further authenticity tests. The check lever 30 is cooperable with cradle 28 to preclude rotation of the latter by undersize coins because of engagement of leg 32 of lever 30 with the shoulder 34 of cradle 28, unless the quarter is of proper diameter.

Coins of smaller diameter than quarters pass between the spaced legs of cradle 28 and are thereby directed downwardly along a path adjacent side wall 14 by virtue of suitable projections on the inner face of the gate unit 18. Thus, the elongated projection 39 extending outwardly from the main planar section 36 of gate unit 18 adjacent the side margin 38 thereof (FIG. 2) is cooperable with the upper end of the quarter coin track 40 integral with planar section 36, to define a coin entrance for pennies, dimes and nickels which pass between the spaced legs 28a and 28b of quarter cradle 28. As is apparent from FIG. 1, the cradle 28 is mounted for rotation on the outer face of planar section 36, with the gate unit 18 having apertures therein for clearing the legs 28a and 28b, and by the same token, the nickel cradle 42 is likewise mounted on the outer face of planar section 36 and has spaced legs 42a and 42b thereon which extend through suitable apertures therefor in planar section 36. Thus, nickels passing through the opening between projection 39 and track 40, come to rest on the legs 42a and 42b to effect counter-clockwise direction of cradle 42 as shown in FIG. 1 whereby the nickels are discharged onto an inclined nickel track 44 spaced below track 40. Nickel cradle 42 is also provided with counterbalance means thereon for maintaining the cradle in the normal disposition of the same illustrated.

The structure forming the subject matter of the present invention for separating pennies from dimes and to direct corresponding coins into the coin tracks or pathways therefor, is also mounted on planar section 36 of gate unit 18, and positioned immediately below the nickel cradle 42. The lower projection 46 on planar section 36 at the margin 38 of gate unit 18, cooperates with the upper edge of nickel track 44 to present an entranceway for pennies and dimes that pass between the legs 42a and 42b of nickel cradle 42. The lower extension 48 of planar section 36 is provided with a semicircular opening 50 therein as best shown in FIG. 2, which sets off a lower, generally circular portion 52 of extension 48. The circular portion 52 serves as means for mounting a horizontal pivot pin 54 that projects outwardly from planar section 36. A dime diverting element broadly designated 56 along with a penny cradle generally numerated 58, are mounted on pivot pin 54 for rotation about the axis thereof.

As is apparent from FIGS. 1, 9 and 10, main wall 12 of frame 11 has an irregularly shaped, generally rectangular aperture 60 therein substantially aligned with cradle 58 and the dime diverting element 56. It is to be pointed out that the aperture 60 extends toward the central area of main wall 12 from side wall 14, and that the horizontal width thereof or the distance between upright margin 60a of opening 60 and side wall 14 is slightly greater than the normal diameter of a United States dime, and may in fact be greater than the diameter of a penny because close tolerances are not required on the size of this opening. However, in order to expedite passage of a dime through aperture 60 as will be explained hereinafter, the lower margin 60b of planar section 36 defining the lowermost edge of aperture 60 is slightly rounded at the intermediate area thereof to generally conform to the circular edge of a coin. Also, the rearmost face of planar section 36 is beveled at margin 60b (FIGS. 9 and 10) to facilitate downward movement of a dime after the same has been diverted through aperture 60 by element 56.

Returning to the construction and configuration of element 56, it can be seen from FIGS. 7 and 8 that such element includes a main generally circular body portion 62 provided with an aperture therein receiving the pivot pin 54, while a lower inclined, elongated extension 64 is integral with the lower margin of body portion 62 and projects toward and extends partially through the aperture 60 in main wall 12. The lower extremity of extension 64 is of pointed and beveled configuration to assure that the latter clears margin 60b defining the lower edge of aperture 60. Another downwardly extending projection 66 on body portion 62 and located to the right of extension 64 viewing FIG. 2, operates as a counterweight to maintain element 56 substantially in the location of the same illustrated in FIGS. 1, 2, 9 and 10. It is now to be recognized that the dime diverting element 56 is mounted for free swinging movement on pivot pin 54.

The penny cradle 58 has a central section 68 also provided with a centrally located opening therein for clearing pivot pin 54 and a pair of generally L-shaped leg portions 70 and 72 are integral with central section 68 and project outwardly therefrom. The inturned, parallel, horizontally spaced outer legs 70a and 72a of penny cradle 58 are spaced apart a distance to receive a penny 74 thereon as is indicated in FIG. 3. It is to be noted that the leg 72a moves in the arcuate opening or slot 50 in planar section 36, whereas the leg 70a shifts through a circular path beneath portion 52 of planar section 36. A counterbalance 76 mounted on central section 68 and in surrounding relationship to pivot pin 54 operates to bias cradle 58 in a counterclockwise direction to shift leg 72a into engagement with the lower portion of extension 48 defining arcuate slot 50, or leg 70a into engagement with the lower margin of planar section 36, depending upon the relative disposition of leg portions 70 and 72. Thus, the leg portion 70 of cradle 58 is normally disposed in

a substantially horizontal position when cradle 58 is in the stand-by position of the same.

Although not illustrated in detail, it is to be recognized that a plate member 78 is pivotally or otherwise mounted on the rear face of main wall 12 behind aperture 60 and normally spaced from the outer face of wall 12 to present a dime passage 80 leading to the dime testing pathway of apparatus 10. Thus, it is to be pointed out that a dime track is mounted on the inner face of plate member 78 below aperture 60 and inclined in a direction to cause the dime to roll along a path across the lower section of frame 11 and through conventional testing structure.

The penny testing section of apparatus 10 includes a main plate 82 removably mounted on the lower portion of the front face of frame 11 and provided with structure thereon presenting a coin track or pathway for pennies across the front of the coin selecting apparatus and in generally parallel relationship to the path of travel of dimes across the rear face of main wall 12. Since the actual construction of the penny runway forms no part of the present invention, the same has not been illustrated in detail. However, it is to be noted that the plate 82 is provided with ear means thereon adjacent side wall 14 carrying a horizontal pin 84 which serves as means for mounting a pair of downwardly extending plate elements 86 and 88. The plate 82 is in spaced relationship from the outer face of wall 12 and presents a coin reject passage for pennies, while a shiftable deflection element 90 is located in the space between plate 82 and wall 12 for preventing movement of pennies into the rejection passage when the upper extremity of deflection element 90 is located adjacent wall 12 as shown in FIGS. 9 and 10. The means for shifting element 90 in a direction to move the upper end thereof away from wall 12 may comprise a lever arm 92 pivotally mounted on plate 82 and adapted to be operated by mechanism forming a part of the handling equipment located in the vending machine or other coin controlled machine. Thus, when deflection element 90 is in the normal location thereof as shown in FIGS. 9 and 10, a penny 74 gravitates from cradle 58 onto the inclined face of element 90 and is thereby caused to pass into the space between plate 82 and the inner face of plate element 88 whereby the inwardly extending legs 96 on plate element 86 and received in suitable apertures 98 therefor in plate element 88, cause the penny to be deflected to the right viewing FIG. 1, for passage along a generally inclined path across the face of plate 82. It is to be understood that a chute member 100 may be provided on the outer face of plate 82 and in an inclined location across the width thereof, to define a coin pathway for pennies and to direct the same into the totalization mechanism of the coin handling equipment.

In operation, quarters and nickels introduced into the entrance of apparatus 10 are diverted into respective coin pathways therefor by the cradles 28 and 42 whereas pennies and dimes entering apparatus 10 pass between the legs of cradles 28 and 42 and thereby gravitate along the coin receiving pathway defined in part by projection 46 and nickel track 44. A penny 74 gravitating downwardly toward the cradle 58 engages the legs 70a and 72a and thereby comes to rest on leg portions 70 and 72. Since the center of gravity of the penny is located to the right of pivot pin 54 viewing FIG. 1, the cradle 58 will rotate in a clockwise direction since the counterbalance 76 is not sufficient to retard rotation of the cradle under the weight of a penny thereon. As is clear from FIG. 3, the penny 74 also engages a central portion of the extension 64 on element 56, and therefore the latter is rotated along with cradle 58 to move extension 64 out of the path of travel of the penny as the same falls from the leg 70a of cradle 58. The penny then falls from cradle 58 onto the inclined surface of element 90 and is directed to the penny chute 100 as previously described. Reference is made to FIG. 2 for a showing of the path of travel of a penny 74 as the same gravitates downwardly along the face of planar

section 36 from the coin entranceway of the apparatus 10, to the cradle 58 for testing the size and weight of the coin.

However, if a dime is introduced into apparatus 10, the coin 102 travels downwardly along the same path as the penny illustrated in FIG. 2, and the dime will pass between the legs 70a and 72a of cradle 58 since the dime is of lesser diameter than a penny. FIG. 5 shows the disposition of a dime 102 as the same commences to move between the legs 70a and 72a of cradle 58, and continued gravitation of the coin downwardly effects diversion of the same by extension 64, through aperture 60 into the dime passage 80. It is to be understood that conventional coin testing means will be provided in association with the coin track or pathway for dimes along the rear face of main wall 12, to determine if the disc which has been diverted through aperture 60 is authentic and of proper size and weight as well as of required material.

In the event a coin or disc comes to rest on the legs 70a and 72a of cradle 58 and not of sufficient weight to effect rotation of such cradle, the disc may be scavenged from legs 70a and 72a by the operator of the vending machine scavenging apparatus 10 in a conventional manner. Although the structure for effecting the scavenging operation is not detailed in the drawing, it is to be recognized that manually operable components are coupled to the gate unit 18 for shifting the latter toward scavenger section 24 whereby the outer, inwardly directed legs thereon push discs or the like located on the legs of the various cradles, off of the cradle supports and thereby effect return of the discs or coins to the front part of the machine through the coin return chute aligned with the lower left-hand corner of the apparatus 10 as illustrated in FIG. 1.

There are many advantages inherent in the dime and penny separating mechanism of the present invention including the fact that the apparatus 10 can be readily adapted for handling of various sizes of coins whether of United States or foreign denomination, inasmuch as it is only necessary to properly space the legs of the various cradles in order to test coins inserted in the machine, for proper diameter and weight. For example, the legs 70a and 72a of cradle 58 may be spaced in closer relationship or farther apart as required to handle coins of a size different from a United States penny. Furthermore, this alteration may be made without interfering with the main cast parts of the over-all apparatus and permitting the conversion of the unit at a minimum cost. Additionally, the relative locations of the legs on the cradles may be adjusted to very close tolerances in a minimum of time and on each individual unit, whereas in prior apparatus, very close dimensions were needed in cast parts which were difficult to obtain at a reasonable cost.

The penny-dime separator of apparatus 10 is also an improvement over prior units in that more accurate sizing of the coins is obtained by virtue of the fact that a positive determination is made of the genuineness of pennies, whereas dimes which pass between the legs of the penny cradle 58, are diverted through the aperture 60 of non-critical size and with the dime being required to pass between such legs before entering the aperture. In this manner, the dime will be properly aligned with the aperture and also moved at an angle with respect to the normal path of travel of a penny gravitating from cradle 58 during rotation thereof. This prevents pennies from passing into the dime passage 80 under any conditions of operation, and also operates to preclude entrance of dimes into the penny pathway.

Also of importance is the construction of dime diverting element 56 so that the kinetic energy of the penny during rotation of the latter on cradle 58, serves to swing element 56 into a location with the extension 64 out of the path of travel of the penny, and thereby obviating other components for shifting element 56 to clear the

path for pennies directed into the penny pathway from cradle 58.

Having thus described the invention what is claimed as new and desired to be secured by Letters Patent is:

1. In coin selecting apparatus for separating coins of one denomination and size from coins of a second denomination and smaller size and including structure defining an upright coin receiving pathway and a pair of coin accepting pathways for coins of respective denominations and extending from the lower portion of the coin receiving pathway, the combination of a member pivotally disposed substantially at the zone of juncture of said pathways and including means thereon for engaging each of said one denomination coins and adapted to divert the latter into the coin accepting pathway therefor as the member is pivoted about the axis of rotation thereof by said one denomination coins, said means being disposed to pass said second denomination coins therethrough; and a coin diversion element positioned to engage second denomination coins passing through said means on the member and divert the same into said coin accepting pathway for the same, said element being movable by a one denomination coin and with the member as the latter is rotated by said one denomination coin, to a location out of the path of travel of the one denomination coin as the latter is diverted into said coin accepting pathway therefor.

2. Coin selecting apparatus as set forth in claim 1 wherein said element is positioned to direct said second denomination coins along a path substantially at a right angle with respect to the path of the one denomination coins as the latter are diverted into the coin accepting pathway therefor by said member.

3. Coin selecting apparatus as set forth in claim 1 wherein said element has an extension thereon positioned to be engaged by coins of both denominations whereby coins of said second denomination are diverted by the extension into the coin accepting pathway therefor while coins of said one denomination engaging the extension cause the element to be moved with the member to shift the extension out of the path of each of the one denomination coins as the same are diverted into the coin accepting path therefor.

4. Coin selecting apparatus as set forth in claim 3 wherein said element is mounted for rotation about a common axis with the member.

5. Coin selecting apparatus as set forth in claim 4 wherein said member comprises a cradle having a main body mounted for rotation about said common axis, and a pair of generally parallel, horizontal legs extending laterally from the main body and adapted to receive a coin of said one denomination thereon in bridging relationship to said legs.

6. Coin selecting apparatus for separating coins of one

denomination and size from coins of a second denomination of smaller size comprising a normally upright wall having structure on one face thereof defining an upright coin receiving pathway; first means on said one face of the wall adjacent the lower extremity of said coin receiving pathway presenting a first coin accepting pathway for said one denomination coins and extending downwardly from the coin receiving pathway; second means on the other face of the wall adjacent the lower extremity of said coin receiving pathway defining a second coin accepting pathway for said second denomination coins, said wall being provided with an opening therein adjacent the junction of said coin receiving pathway and the second coin accepting pathway for clearing coins of said second denomination; a member pivotally disposed on said one face of the wall substantially at the zone of juncture of the coin receiving pathway and said first coin accepting pathway, said member being provided with spaced leg means thereon for engaging each of said one denomination coins and adapted to divert the latter into said first coin accepting pathway as the member is pivoted about the axis of rotation thereof by said one denomination coins, said leg means being disposed to pass said second denomination coins therebetween; and a coin diversion element rotatably mounted on said one face of the wall for rotation about the axis of swinging movement of the member and provided with an extension thereon normally aligned with said opening in a position to engage second denomination coins passing between said leg means and thereby divert the same into said second coin accepting pathway, said extension being located to be engaged by a one denomination coin while the latter rests on said leg means of the member to effect swinging of the element with the member during rotation thereof by said one denomination coin, to a location with said extension out of the path of travel of the one denomination coin as the latter gravitates into said first coin accepting pathway.

7. Coin selecting apparatus as set forth in claim 6 wherein said extension is of elongated configuration and extends through said opening.

8. Coin selecting apparatus as set forth in claim 6 wherein said extension is located at an acute angle with respect to said wall.

9. Coin selecting apparatus as set forth in claim 8 wherein said element is provided with counterbalance means biasing said extension thereon toward said normal position of the same.
